UNITED STATES PATENT OFFICE.

RUSSELL B. TEWKSBUZY, OF CLEVELAND, OHIO, ASSIGNOR TO THE OSTER MANUFACTURING COMPANY, OF CLEVELAND, OHIO, A CORPORATION OF OHIO.

DIE-STOCK.

1,082,292.

Specification of Letters Patent.

Patented Dec. 23, 1913.

Application filed April 22, 1912. Serial No. 692,373.

To all whom it may concern:

Be it known that I, RUSSELL B. TEWKSBUZY, a citizen of the United States, residing at Cleveland, in the county of Cuyahoga and 5 State of Ohio, have invented a certain new and useful Improvement in Die-Stocks, of which the following is a full, clear, and exact description.

The improvement in die stocks, herein 10 shown and described, are designed to produce a strong, durable, and inexpensive tool, which may be organized to cut tapered threads on pipe of different diameters, and to automatically withdraw the dies from 15 the work when the required length of thread has been cut, and to hold them out while the die carrier and work holder are moving to their proper relative positions for beginning the thread cutting operation and to automatically 20 return the dies to proper working positions at such time.

The invention consists of the construction and combination of parts hereinafter described and pointed out definitely in the 25 claims and shown in the accompanying drawings in which—

Figure 1 is a central longitudinal sectional view and Fig. 2 is a front end view of a die stock embodying the invention.

30 The work holder 1 is of familiar construction, being a built up member of tubular form so that the pipe or other cylindrical piece of work to be threaded may be passed through it, and being provided with 35 suitable means whereby it may be clamped to said work. The die carrier 2 is likewise tubular and is capable of moving rotatively and longitudinally relative to the work holder. In the construction shown the die 40 carrier has its rear end externally threaded so that it may screw into the internally threaded work holder; wherefore as the die carrier is turned relatively to the work holder it will move longitudinally relative 45 thereto at such a rate as is determined by the pitch of the engaging threads upon these two parts.

At the front end of the die carrier is an outwardly extended flange 2^a which is provided with a plurality of pairs of forwardly 50 projecting lugs 2^b and 2^c which form radial guideways for the chasers or dies 3. In the particular construction shown the dies do not themselves engage directly in these 55 guideways, but are fixedly held in die cases

4; and it is these die cases which directly engage with the guide lugs referred to. The employment of die cases is an old expedient in this art and nothing new is claimed for it herein. In fact, it is a matter of no consequence to the present invention whether the dies directly engage the guide lugs or whether they are immovably held in cases which engage said guide lugs. 60

Each of the die cases has two laterally 65 projecting ribs 4^e on its side which engage in corresponding grooves in the inner faces of the guide lugs. The dies fit nicely in these cases; and their rear ends, as shown, abut against shoulders 4^b near the rear ends of 70 the cases. Gibs 4^a secured to the top walls of the cases overhang the dies and hold them immovable in said cases.

5 represents a ring which is rotatively mounted upon the work holder, but is held 75 against longitudinal movement relative thereto. The particular means shown for preventing said longitudinal movement without interfering with the rotative movement, include a circumferential groove 1^a in 80 the work holder, and one or more pins 5^a which screw through the ring and project into this groove.

6 represents templet bars which are fixed 85 to this ring and extend longitudinally therefrom forward through suitable openings in the flange 2^a of the die carrier. Essentially there is one of these templet bars associated with each die. Each of these templet bars has a guideway for engagement, directly or 90 indirectly, with the associated die. In the specific construction shown these several templet bars are formed integral with the ring 5. This, however, is immaterial because the essential thing is to have the templet bars rigidly fixed to the ring while the tool is cutting threads. In the construction shown each templet bar is bifurcated and the associated die passes between the two 95 branches of the bar. This, however, is also 100 immaterial insofar as the present invention is concerned, because only one bar which passes on one side only of the associated die is required. By bifurcating the templet bars and allowing the two branches thereof to engage the outer faces of the ribs 4^e on the die cases the templet bars and ring are 105 compelled to rotate with the die carrier in both directions. Any other means, however, which will compel the simultaneous rota- 110

tion of the ring with the die carrier, but which will permit the templet bars to move longitudinally relative to the die carrier should be regarded as the equivalent of the particular construction shown.

5 The so-called guideway with which each templet bar is provided is an inclined groove 6^b in that face which is adjacent to the associated die case; and a pin 4^c fixed to and 10 projecting laterally from the associated die case projects into this guide groove. If the die stock is to be organized to cut tapered threads, this groove will be inclined to the axis of the tool at the required inclination.

15 If, in using the tool, the die carrier be screwed into and out of the work holder such distances as will always keep said pin in the straight part of said guide groove, as shown, the dies will be gradually retracted or allowed to retract, as the case 20 may be, as the die carrier is screwed into the work holder, and this will result in the cutting of a tapered thread. Moreover, as the die carrier is screwed out of the work 25 holder said dies will be moved in the contrary direction and will assume the required position for starting to cut a new thread when the die carrier has been screwed out of the work holder far enough.

30 If it is desirable to adapt the tool to cut threads on pipe of different diameters a second guide groove, as 6^c, may be provided in each of the templet bars. In the particular construction shown the pins 4^c screw into 35 the sides of the die cases and are introduced into the groove 6^b through the open front end thereof.

If it is desired to endow the die stock 40 with the capacity for automatically moving the dies clear of the work, after the required length of thread has been cut, and for holding them in the withdrawn position until the die carrier and work holder having been unscrewed, and of returning them to working 45 position, when the work holder and die carrier have been returned to the proper relative position for starting the cutting of a thread, these two grooves 6^b and 6^c may be joined at their upper and lower ends substantially in the manner shown in the drawing, so as to form a single endless guide 50 groove. That is to say, there will be an outwardly curving groove 6^d formed as a continuation of the lower end of the inner groove 6^b, and this will join the lower end 55 of the groove 6^b. There will also be an inwardly curving groove 6^e as a continuation of the upper end of the groove 6^c which will join the upper end of the groove 6^b.

60 It is clear that as the die carrier is screwed into the work holder with the pins 4^c in the grooves 6^b said pins will travel down in said grooves and thereby the dies will be compelled to move, or will be definitely controlled in a movement outward or in the re-

ceding direction. When each pin reaches the curved lower end 6^d of its guide groove, it will be drawn rapidly outward, and the dies will be entirely withdrawn from contact with the work. When the die carrier is now 70 turned in the reverse direction relative to the work holder the pin will travel upward in the groove 6^c and will be held out of possible engagement with the work until the upper curved end 6^e of the groove 6^c is 75 reached. Then the pin 4^c, as it moves in said groove, will be moved inward and the die will be moved with it until the pin comes over the upper end of the groove 6^b. By now screwing the die carrier into the work 80 holder the pin will enter the groove 6^b and the described operations will be repeated.

In the foregoing description particular reference has been only made to one pin, to one templet bar and to the guide grooves 85 therein, but it will be understood that similar grooves are formed in all of the templet bars, and that all of the dies will have the same movement by reason of the projection into the grooves of the associated templet 90 bars of the associated pins 4^c.

Having thus described my invention, I claim:—

1. In a die stock, the combination of a work holder, a die carrier which is rotatively and longitudinally movable relative to the work holder, radially movable dies carried by the die carrier, a ring which is rotatably mounted upon the work holder, but has no longitudinal movement thereon, templet 95 bars fixed to said ring and extending longitudinally forward, each templet bar having two parallel inclined guide grooves, a pin rigidly fixed to each die and adapted 100 to enter either of said guide grooves, and means compelling said ring to rotate with 105 said die carrier.

2. In a die stock, the combination of a work holder, a die carrier which is rotatively and longitudinally movable relative to the work holder, radially movable dies carried by the die carrier, a ring which is rotatably mounted upon the work holder, but has no longitudinal movement thereon, templet bars fixed to said ring and extending longitudinally forward, each having an endless guideway which includes two branches which extend in a general longitudinal direction side by side,—the branch nearest the axis having its rear end curved away from the axis and connected with the other branch and the branch farthest from the axis is at its front end curved toward the axis and connected with the front end of the other branch, a device fixed to each die engaging said endless guideway in the associated templet bar, and means compelling said ring to rotate with said die carrier.

3. In a die stock, the combination of a work holder, a die carrier which is rotatively 130

and longitudinally movable relative to the work holder, radially movable dies carried by the die carrier, a ring which is rotatably mounted upon the work holder, but has no longitudinal movement thereon, templet bars fixed to said ring and extending longitudinally forward, each templet bar having two parallel guide grooves of which the one nearest the axis is curved near its rear end outward and connected with the rear end of the other guide groove, and of which the front end of the guide groove farthest from the axis is curved inward at its front end

and connected with the front end of the other guide groove, a pin rigidly fixed to each die and projecting into said guide grooves, and means compelling said ring to rotate with the die carrier.

In testimony whereof, I hereunto affix my signature in the presence of two witnesses.

RUSSELL B. TEWKSBURY.
